FURNITURE CUSHION OR SIMILAR ARTICLE

Christen Wilhner Sorensen, 210 Darwin Park, Nun's Island, Montreal, Quebec, Canada

Filed Oct. 24, 1969, Ser. No. 19,706

Claims priority, application Canada Sept. 29, 1969

Term of patent 14 years

Int. Cl. D6—01

U.S. Cl. D15—8

FIG. 1 is a perspective view of the furniture cushion or similar article embodying the design of the present application;

FIG. 2 is a side view of the article of FIG. 1;

FIG. 3 is an end view of the article of FIG. 1, and

FIG. 4 is a bottom view of the article of FIG. 1.

The dominant feature of my design resides in the substantially transversely extending double ogee concavity extending along a major surface from the juncture of the major surface and another surface, which double ogee concavity terminates significantly short of the opposite end of the major surface.

I claim:

The ornamental design for a furniture cushion or similar article, as shown and described.
